CLAIM

The ornamental design for an eyewear device, as shown and described.

DESCRIPTION

FIG. 1 is a top-front perspective view of an eyewear device first embodiment.

FIG. 2 is a back perspective view of an eyewear device first embodiment.

FIG. 3 is a back view of an eyewear device first embodiment.

FIG. 4 is a front view of an eyewear device first embodiment.

FIG. 5 is a side view of an eyewear device first embodiment.

FIG. 6 is a side view of an eyewear device first embodiment opposite the view in FIG. 5.

FIG. 7 is a top view of an eyewear device first embodiment; and,

FIG. 8 is a bottom view of an eyewear device first embodiment.

Any usage of dashed line(s) in the claims is provided merely for context and does not represent a part of the design. The stippling in the drawings represents shading and forms no part of the claimed design.
